AUTOMATIC RADIO PROGRAM SELECTOR

Robert H. Verkins, Minneapolis, Minn.

Application November 23, 1933, Serial No. 699,452
Renewed May 24, 1937

32 Claims. (Cl. 250—20)

My invention relates to automatic radio program selectors and has for its object to provide means whereby any radio receiver can have predetermined selected settings made covering any 5 of a group of stations and selected periods of time over a day of a week, or in which such predetermined setting for selected program as to stations and times may be continued from week to week without re-setting, all in combination 10 with means whereby said several selected programs, at the times and over the stations predetermined and set on the apparatus, will be automatically tuned in and the proper or suitable volume of reception be set, successively from 15 program to program throughout the entire range of selected settings.

The invention consists in the combination of several different sets of instrumentalities for effecting the above broadly-stated objects and 20 purposes of the invention. These instrumentalities are: First, a series of manually operated actuating devices sufficient in number and so arranged as to provide an actuating device for any selected station at any predetermined time (quarter hourly, half hourly or hourly) which may be desired, together with conveniently positioned manually operative means preferably appearing on the front of the radio casing whereby such settings may be simply and easily made; second, 25 to provide a power-driven timing actuator to move the said setting device and thereby to cause it to actuate the instrumentalities for tuning in the selected station and setting the volume thereof; third, to provide in combination with the tuning means of a radio receiver a power-driven member connected to positively operate the tuning means in combination with means for positively stopping and holding the movable member 30 at a point in its movement determined by the selected station such that said station will be positively and precisely tuned in; fourth, to provide a single operating member having adjustable parts corresponding to the several stations of the whole group of stations from which 35 selection is to be made which member has connection with the volume control of the radio receiver and is rendered operative to set said volume control by the stopping of the tuning means; fifth, the various instrumentalities for 40 tuning in selected stations at predetermined times and setting the volume of reception therefor, are associated with signal means such that a visual signal appears for a program to be selected and tuned in.

55 In reference to the first of the above features

of the invention, it is an object of my invention to provide a manual means for conveniently selecting and setting actuators for any series of programs over time intervals for a day or a week, and in any of a group of stations available to 5 the operator, and associated with the manually operated devices for setting the actuators are also manually operative devices for manually cancelling any such setting as may be desired. These devices embody a movable holding member specifically a drum, provided with transverse and longitudinal rows of actuating members to be set, the transverse rows indicating time intervals and the longitudinal rows indicating stations, in combination with a device adapted to be moved 10 longitudinally over the longitudinal rows and transversely along the transverse rows, the longitudinal movements being effected by a manual member applied to a dial carrying time interval indications, and the transverse movements being 15 effected by a manual member applied to a dial indicating stations to be selected.

In reference to the second of the above features of the invention, it is an object of my invention to provide a power device, specifically a 20 pulsator motor driving operating members which rotate in timed relation, for example, one member which rotates in exactly one minute and a second member which rotates in exactly thirty minutes, with means on the one minute member 25 adapted to engage means positioned by the thirty minute member to actuate the movable member of the first feature of the invention whereby if a station and time is set other instrumentalities are rendered active to tune in the station at that 30 time and set the volume therefor. These timed devices also under those conditions actuate or render active means for putting the said indicator out of position or into inoperative position, and means for effecting signaling operations as 35 hereinafter pointed out.

In reference to the third of the above features of the invention, it is an object of my invention to provide in combination with tuning means of a radio receiver a movable member having thereon a multiplicity of elements corresponding to a selected group of stations each element having a stop positioned thereon relative to the movement of said member at a point corresponding to the tuning position of the member for a given 50 station, together with a movable device for each of said station representative elements which is set for time and station by the means hereinbefore referred to so as to be automatically actuated into position to engage the stop on that 55

movable member and terminate the movement of the member at the exact point where through its connection with the tuning means of the radio receiver it has reached the tuning position 5 of the selected station, together with power means for moving the member and tuning means of the radio receiver.

In reference to the fourth of the above features of the invention, it is an object of my invention to provide in combination with the volume control of a radio receiver a movable member adapted to operate in its movements said volume control, to fix on said member a multiplicity of stop members each corresponding to one of the 15 stations of the group controlled by the device, and each adapted to be adjustably positioned so that when it operates to stop movement of the member it will have moved the volume control to set the correct volume for that station, in combination with means, which may be associated with the tuning stop devices, for being brought into position for the selected station to be engaged by said adjusted stop and thus set the tuning means of the radio to the precise 20 proper tuning position for the selected station.

In reference to the fifth of the above features of the invention, it is an object of my invention to provide visual signals, which may be in the form of bright lights showing just before a selected program will start to call attention to the 25 imminence of such program and permit it to be continued or cancelled as desired.

Other objects of the invention consist in providing various details of construction whereby the 30 operation and functioning of the several features of invention above-outlined may be effected either manually or automatically as called for so as to produce accurate, certain and always dependable results. It is to be understood, however, that the specific embodiment of structural 35 features herein described are not to be regarded as limiting the invention or specific parts thereof to such precise details, but that modification and substitution of equivalent structures are contemplated within the scope and purpose of the invention.

The full objects and advantages of my invention will be more particularly pointed out in the specification and drawings, and its novel features are particularly pointed out in the claims.

In the drawings, illustrating an application of my invention in one form—

Figure 1 is a front elevational view of an automatic controller for a radio receiver set;

Figure 2 is a side elevational view thereof;

Figure 3 is a similar view from the other side shown partly broken away;

Figure 4 is an enlarged section on line 4—4 of Figure 3;

Figure 5 is a top plan view, partly in section, and partly broken away;

Figure 6 is an enlarged sectional detail on line 6—6 of Figure 3;

Figure 7 is an enlarged detail section on line 65 7—7 of Figure 6;

Figure 8 is an enlarged transverse section on line 8—8 of Figure 1;

Figure 9 is an enlarged sectional view taken on line 9—9 of Figure 1;

Figure 11 is a sectional elevational view on line 11—11 of Figure 1;

Figure 12 is an enlarged detail elevational view 75 of a cancelling device;

Figure 13 is a side elevation thereof;

Figure 14 is an enlarged detail of a pin-tension arrangement;

Figure 15 is an enlarged detail elevational view of a pin;

Figure 16 is an enlarged fragmental plan view of a tensioning device;

Figure 17 is an enlarged sectional view on line 17—17 of Figure 3;

Figure 18 is a section on line 18—18 of Figure 4;

Figure 19 is a detailed perspective view of a portion of Figure 18, looking from the top thereof;

Figure 20 is a perspective view of the cancelling mechanism;

Figure 21 is a detail of a shaft locking mechanism, certain parts being shown exaggerated;

Figure 22 is an enlarged detail view of a switch; and

Figure 23 is a wiring diagram.

Like reference characters indicate like parts throughout the specification and in the various figures of the drawings, in which 1 indicates conventionally, a radio set in connection with which 25 operates my automatic program selector designated in general by the numeral 2 and carried by a support 3. The different sets of instrumentalities referred to in the preceding statement of invention will now be described in detail 30 and in the order stated.

Manually operated setting means

In order to accomplish manual setting of the machine for any selected radio station at any 35 predetermined time, I provide a drum 47 which as best shown in Fig. 5 has a hub 104 mounted for rotation around a shaft 102 by power driven means to be described later which operates in connection with an internal ring gear 46 carried by the drum. The periphery 51 of the drum 47 40 in the embodiment as shown in Fig. 1 is divided into seven day sections 52 and seven night sections 53, the day sections including the time between 7 A. M. and 10 P. M. while the night sections include the remaining time of a twenty 45 four hour period. The surface of the drum 47 is provided as shown in Fig. 2 with ten circumferential or longitudinal rows 54—63 which as will be understood from Fig. 14 are separated by grooves 64, 65, etc., which are beveled as shown 50 in this figure. There are twenty of these grooves and strung tightly therein so as to lie in the bottom of the beveled grooves are fine piano wires 66, 67 etc. Each of the circumferentially disposed rows in each of the day sections 52 has 55 thirty bores 70 extending entirely through the periphery of the drum. As will be understood from Fig. 16, the periphery of each bore at opposite sides thereof lies in the path of the piano wires as at 70' and 70''. Seated in each bore is 60 a pin 71, the opposite sides of which are flattened as indicated at 72 and 73 in Fig. 15.

Every pin, of which there are thirty in each row of each day section, is provided with a transverse groove 74, at the lower end of its flattened 65 portion 72 on one side (Fig. 15) and a similar groove 75 at the upper end of its flattened surface 73, on its other side, which grooves 74 and 75 are alternately engaged by one of the wires 66 and 67, the spring tension of which holds 70 said pins raised or lowered in their respective bores until shifted one way or the other against said tension. In order that said pins, so closely seated relative to one another, will not interfere with the tension of said wires on adjoining pins, 75

said pins are alternately reversed in their respective bores and columns. A groove 74, will be engaged by a wire 68, at the bottom of the flattened surfaces of each pin, the adjoining pin 5 groove being engaged by wire 67, this arrangement being reversed on each adjoining pin throughout its circumferential columns 69. These pins are adapted to be pressed back and forth in the bores, as will be later more fully explained. However, the spring tension of said piano wire will cause a clicking sound, as a pin is moved in one direction or the other, which "click" will signify to a person operating the device that the pin is moved to its desired position. Each of these 10 pins is provided with a tapered inner end 76, and a ball-headed outer end 71, for purposes which will later appear.

Every pin 71 in each circumferential row, 54 to 20 63 respectively, represents one and the same radio station, as indicated on a station indicating dial 78 (Fig. 1) upon which selected stations may be written by the user. These selected stations indicated on this dial, may be changed at will. Every group of pins 71 in the peripheral columns 25 represents days of the week, as indicated on a day indicating dial 79 (Fig. 1) wherefore, each pin represents a radio station, and a half-hour period of the day. These pins are, as above explained, movable back and forth in their bores 30 through the periphery of drum 47. When moved in for selecting a program, their tapered ends lie in the path of a station selecting device 80 mounted within the drum (Figs. 9, 12 and 13) and at the proper time will operate said device 35 to bring in the desired station, as will later herein-after more fully appear. In order to move these pins in to select a desired station and program, I provide a revoluble arm 81 (see Fig. 5) having a right-angular head 82, through the terminal 40 83, of which a push-pin 84 operates. On the inner end of the pin is a concave socket 85, which, when pushed down upon the ball-end 71 of a pin 71, will center itself directly over the pin.

Pivoted at 86 on said head 82, is a bell-crank 45 lever 87, one arm 88 of which rests upon the head 89 of pin 84 in order that when the arm 90 of said crank is drawn rearward by a link 91, the arm 88 will push in the pin 84 to, in turn, push in one of the pins 71. The link 91 is connected 50 on one arm 92 of a bell-crank lever 93, pivoted at 94 to the member 81, and its other arm 95 is connected to a link 96 which, in turn, is connected at its other end to the arm 97 of a third bell-crank lever 98, the other arm 99 of which 55 lies against the outer end 100 of a push-rod 101, slidably mounted in a tubular shaft 102, upon the end 103 of which the arm 81 is clamped. The shaft 102 is rotatably and slidably seated in the axle 104 of drum 47. Through said rotatable 60 and slidable action of shaft 102, the pin 84 may be shifted to position directly in alignment with any pin 71 in the drum 47, as the head 82 rotates around the periphery of said drum and moves transversely thereof. A spring 105 coiled around 65 pin 84 holds the pin as well as arm 88 normally in outermost position through which action and the connecting links, the arm 99 is held against push-rod 101.

The shaft 102 is rotated in the following manner: Knob 106 fixed to shaft 107 is manually rotated and operates through a tubular shaft 108. The knob has fixed thereto an indicating hand 109 which operates relative to the hour-indicating dial 110. This rotates a gear 111 fixed on the 75 opposite end 112 of said shaft and turns gears

113 and 114 on shaft 115. Gear 114 drives gear 116, fixed on hub 117, which hub is keyed through slots 118 to shaft 102, but through which hub said shaft 102 is slidably, there being preferably two slots similar to slot 118 shown on Fig. 5 on 5 opposite sides of shaft 102. Also fixedly mounted on hub 117 is a relatively wide fibre gear 119 upon the teeth of which a spring-pressed ball 120 bears, (Fig. 4) to check the movement of said last gear, and holds arm 81 in proper position. The rotation of knob 106 then, of course, causes the rotation of shaft 102, and with it the arm 81, whereby the push-pin 84 may be located above any one of the pins 71 in a circumferential row, this location representing a certain half-hour period of the day; thus each pin 71 not only represents a particular radio station, and a day of the week, but also a half-hour period of the day.

The dial 110 is fixed on tubular shaft 108, as also is gear 121, behind said dial, and gear 122 at the other end of shaft 108. The gear 121 is in mesh with a gear 123, rotatable on outer end 124 of shaft 115. Fixed to gear 123, is a smaller gear 125, in mesh with a gear 126, fixed on a hub 127 on which the day-indicating dial 79 is also fixed, and which is rotatable upon a shaft 128, on the outer end of which is fixed a panel 129 and indicating hand 130 operating in conjunction with dial 79. Fixed on the inner end of shaft 128, is a gear 131 in mesh with a gear 132 fixed on shaft 115. Gear 122 is in mesh with internal ring-gear 46 of the drum 47, and is operated through the operation of said drum. The gear-ratio between knob 106 and panel 129, and dial 110 and 79 is seven to one. Knob 106 is fixed on 35 shaft 107 and at the other end of shaft is fixed gear 111. Gear 113 is fixed to gear 114, and both these are fixed to shaft 115. At the opposite end is fixed gear 132, which meshes with gear 131, which is fixed to shaft 128 along with panel 129 40 at shaft's outer end. Panel 129 contains indicating hand 130. Thus, by manually revolving knob 106, arm 81 on shaft 102 rotates, and panel 129 revolves also.

Now, in order to shift head 82 of arm 81 transversely of the drum, across the rows 54, 55, etc. of pins 71, to select certain radio stations for reception, I provide the fixed dial 78, through which a shaft 133 freely rotates by means of a manually operated knob 134, upon which is fixed 45 an indicating hand 135 co-acting with said dial to indicate the location of a radio station marked thereon. To the inner end of the shaft 133 is fixed a pinion 136, operating upon a segmental gear 137 from the pivotal point 138 of which a right-angular arm 139 projects. The free end 140 of this arm is pivotally and slidably attached to the free end 141 of a reciprocating arm 142, through a pin and slot connection 143. The end 144 of arm 142 is pivoted by a pin 145 to the 50 frame member 146. The end 147 of slide shaft 102 is fixed to arm 142, near its end 141, by a pivot clamp connection, 148, whereby, reciprocating movement of arm 142, will slide shaft 102 back and forth to impart a similar movement of 55 arm 81. This arrangement brings the push-pin 84 approximately over a certain pin 71, which represents the radio station to which the indicating hand 135 points on dial 78.

The above operation may be performed either 60 before or after the day and hour indices have been adjusted, as previously mentioned. The same pin will be located by arm 81 in either case. When the push-pin 84 is located over a pin 71, indicating the station selected on dial 78, 75

the day selected on dial 79, and the hour selected on dial 110, as shown by their respective indices, the next step for the person doing the selecting to take is to press down upon a finger-plate 149 (Figs. 1 and 2) on one end of a lever 150, pivoted at 151, to the frame member 152, which lever in turn presses down arm 153 of a bell-crank lever 154, the arm 155 of which is connected through a link 156, the other end of which is connected to the arm 157 of a bell-crank lever 158, to the arm 159 of which is connected a link 160, (Fig. 5) engaging the arm 161 of a bell-crank lever 162, pivoted at 163 and the other arm 164 of which is held into contact at all times with the end 165 of the push-rod 101, operating through shaft 102, through which connection the pressing down of lever 150 will cause lever arm 164 to push rod 101 against lever arm 99, which operates push-pin 34, as previously explained.

However, just prior to this action, the link 167, attached to the protruding heel 168 of lever 158, has drawn a centering pin 169, to which the other end of the link 167 is attached, against the centering bar 170, having a scalloped edge 171, against said edge with sufficient force to cause the point of said pin 169 to slide into one of the notches 172 along said edge, through pressing upon the sides of the arc of the scallops 172, whereby the action of the centering pin will be to cause the arm 142 to slide, together with its parts, including 102, in order that the pin will enter the nearest notch 172, thus moving shaft 102, to exactly center the push-pin 34 over the pin 71 to be acted upon thereby. The last mentioned action is a method of exactly centering push-pin 34 over pin 71 when and if the operator has not set hand 135 in exact position over a station indicated on dial 18. Centering-pin 169 will correct such slight error. The bar 170 is fixed to the frame members 3' and 3''.

Power driven timing actuator

By referring to Fig. 1, it will be seen that a synchronous electric motor 5 is mounted at the lower right hand corner of the supporting frame. A shaft 6 driven by this motor and shown in Figs. 3 and 4, rotates at a speed of seventy five revolutions per minute. A gear 7 secured to the shaft 6 meshes with a gear 1' secured to a shaft which also has secured thereto a gear 1'' meshing with a gear 8, the gear ratio being such that a reduction gearing is provided to drive the gear 8 one revolution per minute. The gear 8 as shown in Fig. 18 is secured to the lower end of a shaft 233 to the upper end of which a ratchet clutch member 234 is secured by a screw 235. The clutch member 234 cooperates with a complementary clutch member 239 slidably attached to the lower end of a shaft 9 by means of a pin 237 on the shaft operating in a slot 238 in the clutch member 239. It is apparent therefore that when the clutch members 234 and 239 are in engagement with each other, the gear 8 will drive the shaft 9, but when the clutch member 239 is lifted by means to be described later, the gear 8 will rotate without rotating the shaft 9. The shaft 9 is provided with a worm 10 which as shown in Fig. 4 meshes with a gear 11 which in this particular embodiment is timed to make one revolution every half hour. By referring to Figs. 3 and 4, it will be understood that the gear 11 is secured to a shaft 21 which through suitable reducing gears 12, 13 and 14 rotates a gear 15 secured to a shaft 23 once every twenty four hours.

A knob 17' shown in Figs. 1 and 3 is secured to a

shaft 240 to which is also secured a pulley 16. A belt 18 is trained over the pulley 16, an idler 19 and a pulley 29 secured to the upper portion 236 of the shaft 9 as shown in Fig. 4. By turning the knob 17', the shaft 9 may be manually turned to set the device for time. Secured to the shaft 21 which carries the gear 11 is a thirty minute dial 22 (see Fig. 1) to indicate proper setting of the machine. Mounted on the outer end of the shaft 23 which carries the twenty four hour gear 15 is a twenty four hour dial 24 for assisting the operator to properly set the machine.

Secured to the gear wheel 11 near the periphery thereof is a pin 25 (Figs. 4 and 19) which once in every thirty minute period engages the beveled end 26 of a lever 27 pivoted centrally at 28, thus lowering the end 29 of said lever and a rod 30 connected thereto. The lower end of the rod 30 as shown in Fig. 18 terminates in a right angular foot 31 which after twenty-nine revolutions of the gear 8 is lowered by the action just referred to, into the path of a pin 32 carried by the gear 8, whereby upon the thirtieth revolution of said gear, the pin 32 will trip the rod 30 thereby operating a lever 33. This lever as shown in Fig. 18 is centrally pivoted at 34, one end 35 thereof being connected to the rod 30 and the other end 36 being connected to one end 37 of a link 38, the other end of which as shown in Fig. 17 is connected at 38 to one end of a lever 40 fulcrumed at 41 to the frame member 249. The other end of the lever 40 is pivoted to a pawl 43 having an end 44 which normally engages the teeth 45 of the ring gear 46 on the drum 47. The movement of the pawl 43 moves the drum, the distance between successive teeth 45 which action is repeated each half hour period. The number of teeth is such that the drum will make one complete revolution in one week. The rod 30 is normally held raised by a spring 30' as shown in Fig. 19 and a spring 40' shown in Fig. 17 retracts the lever 40. In order that the drum 47 will move exactly the proper distance with each movement of the pawl 43, a spring 45 pressed ball 48 is carried in a socket 49 supported by a rod 50 as shown in Fig. 4. The ball 48 engages between adjacent teeth marked 45' and 45''.

As previously stated, the one minute gear 8 carries a pin 32 which trips the rod 30 as shown in Fig. 18. As also shown in this figure, the pin 32 travels in the path of the foot 173 of a bar 174, the upper end of which as further shown in Fig. 19 operates through a hole in the end 175 of a lever 176 which end is normally held raised by a coil spring 177 on the pin 28 on which the lever 176 is pivoted. This spring bears upon the arm 179 of the lever 176 so that its end 180 is held down. The end 180 has an inclined under surface 186 shown in dotted lines in Fig. 19, lying normally in the path of the pin 25 on the half hour gear 11 whereby through the rotation of the gear 11, the pin 25 raises the lever end 180 and lowers the end 176. The bar 174 is thus lowered so that its foot 173 lies in the path of the pin 32 whereby a lever 188 connected to the lower part of the bar 174 as shown more particularly in Fig. 20 and pivoted at 188' will push a link 189 and attached arm 190 of a bell crank 191 and thereby depress the arm 192 of the bell crank. The depression of this arm will through a connecting link 193 depress the arm 194 of a lever 195 pivoted at 196. The other arm 197 of this lever is connected by a link 198 with the 75

end 199 of a lever 200 pivoted at 201. The other end 202 of this lever operates upon a link 203 having a right angular end 204 best shown in Fig. 13 and having a hole therein through which a rod 205 passes slidably whereby the rod 205 will be depressed together with a yoke 206 fixed to its lower end.

The upper part of the rod 205 is provided with a head 207 and with a collar 208 between which is a coiled spring 209. This spring is gradually compressed prior to any action of the rod 205 until after a certain compression is reached, it will depress the rod 205 for the purpose of pushing a pin 71 upwardly of the drum 47 with a snap action. This is accomplished by means of a bar 210 carried by the yoke 206 as will be understood from Fig. 12 from which it is apparent that such pins 71 as are in the path of the bar will be pushed out. Since the bar is always directly above a transverse row of pins corresponding to stations any one of which may just previously have been automatically tuned in, provision is thus made for automatically cancelling or clearing stations after the corresponding pins have once acted. A coil spring 212 (Fig. 20) connected to the link 193 and the lever arm 192 holds the members 189, 191, 193 and 194 in normal position against gravity action while a spring 213 presses the lever arm 199 normally down to overcome the gravity action of the members 203, 209, 205, 206, 273 and 210.

Mounted between the stop 181, (Fig. 18) fixed on the link 174 and the end 175 of the lever 176 is a coil spring 182 which normally holds the head of the link 174 against the lever. However a wedge 183 is slidably mounted on a support 183'. The wedge is provided with a shank 184 having a knob 184' whereby the wedge may be manually pushed under the foot 185 of the stop 181. When this is done, the link 174 is held stationary thereby preventing the automatic pushing out of the pins 71 so that the same program may be obtained week after week without re-setting the pins.

The pin 25 on the half hour gear 11 furthermore travels in the path of a lever 214 pivoted at 28 (Fig. 4), this lever having a straight lower edge indicated by the dotted line 215 in Fig. 19. When the pin 25 is in engagement with this edge, a rod 216 attached to the lever is held lifted. The lower end of the rod is attached as shown in Fig. 8 to the arm 217 of a bell crank 218 so that the arm 219 thereof is lowered together with a rod 220 attached thereto and to the arm 221 of a bell crank 222 (Fig. 10). A coil spring 223 shown in Fig. 8 normally holds the arms 219 and 221 together with the connected rod 220 in raised position. This action is entirely automatic and will be more fully explained later. However in order that the action of lowering the rod 220 may be manually controlled (see Figs. 10 and 11), I connect to the arm 224 of the lever 222, a rod 225 having a slidable connection at 226 with the arm 227 of a lever 228, the other arm 229 of which is provided with a finger plate 230 which may be manually depressed to lift the rod 225. A coil spring 231 on the fulcrum 232 of the lever 228 normally holds the lever in the position shown in Fig. 11.

Normally the machine operates automatically through the action of the synchronous motor 5. However, should the motor be stopped by disconnecting it from its source of energy, it becomes necessary to retime the machine for future operation. In order to do this, it becomes neces-

sary to permit idling of the shaft 9 in order that the timing dials may be reset without interference with other parts of the mechanism. In order to do this, the thirty minute gear 11 normally driven by the worm 10 of the shaft 9 must be rotated by manual action which is accomplished as previously stated by turning the knob 17' fixed to the shaft 240 (Figs. 3, 4 and 5). The hub 241 of the pulley 16 is in the form of a ratchet clutch which in one rotating position 10 turns freely upon the shaft 240 through the action of the ratchet end 243 of said hub and a pin 244 (see Fig. 3) on the shaft 240. A spring 245 on said shaft and bearing between the pin 246 and said hub normally presses the latter toward the pin whereby the pulley 16 will rotate with the shaft 240 in one direction, but idles thereon upon turning said shaft in the opposite direction by the knob 17'. Thus through operation of the knob 17', the pulleys 16 and 20 and 20 the belt 18 rotate the worm shaft 9 free of the gear 8 and the worm 10 drives the gear 11, which sets the timing mechanism into operation. Since the shaft 240 is slidable through the hub 241 with the pinion 247 on the inner end thereof which 25 is normally disengaged from the ring gear 46 through the action of the spring 245, it follows that pressing in and turning of said shaft (which disengages it from fixed connection with the pulley 16), causes the pinion 247 to mesh with 30 the ring gear whereby the drum is driven in one direction only and which in turn through the gear 122 drives the shaft 108 and with it the dial 110 in connection with which a fixed indicating hand operates. The drum may thus be set to 35 proper time. The same operation drives the gears 121, 123, 125, 126, the hub 127 and the dial 129 with which a fixed indicating hand 249 indicates the day, whereby the dials may be set to the day of the week, and the half hour of the day. It 40 should be recalled that the drum 47 is intended to rotate in one direction only and when operating automatically, it is moved one tooth of the ring gear at a time by the pawl lever 43 which movement occurs once every half hour. However it may be turned in the same direction by the pinion 247. The ring gear in turn operates the gear 122 through the connection of which as 45 previously explained, the hour dial 110 and the day dial 129 are rotated in unison therewith. The 50 drum and the dials therefore always move together and the exact day of the week and the time of the program may be read on the dials.

Automatic tuning means

Supported by the up-right frame 249, (Fig. 8) upon which the shaft 102 is also supported is a horizontal shaft 250, projecting inwardly of the drum 47, and adjacent the drum rim or periphery (Figs. 9, 12 and 13). Pivotedly mounted upon the shaft 250 are a series of arms 251, one for each of the circumferential rows of pins, 54, 55, etc. The said arms terminate in substantially V-shaped presser-feet 211, one of each feet directly overlying one of the pins 71 in the transverse 65 rows of pins 71'. Also pivoted on the shaft 250, are arms 252 and 253 of a yoke 254, the head 255 of which turns down at right-angles thereto, and is in the form of a blade 256 which seats normally suspended within the V's of the said 70 presser-feet, said yoke having upwardly projecting bearings 257 and 258 which are pivotally connected to the bar 259 of another yoke 260, to the head center of which is fixed a vertical rod 261, projecting through an aperture in a guide 262. 75

carried by an arm of said vertical support 249. The upper end of said vertical rod 261 is a socket extension 263 and between the lower end of this socket and its guide, is coiled a spring 264 upon said rod, whereby the yoke 260 and blade 256 are held normally raised out of contact with said presser-feet 211. The other arm 255 of the lever 158, has pivoted to its extreme end a rod 266, the end of which operates in the socket 263 over the upper end of the rod 261, whereby upon raising the finger-plate 148 of said lever 158, the rod 266 will be forced down, and in turn force the rod 261 down, and the blade 256 to press down all of the presser-feet and in this manner shove out the pin 71 or pins 71' in the path thereof, whereby stations which had previously been selected by said pin will be shoved outwardly of the drum, manually cancelling same until again used for selecting stations and time. This "cancelling" or pushing out the pins may be done as much as twenty-eight minutes prior to the time of an automatically selected program.

Also pivotally mounted upon the shaft 286, are a pair of lever arms similar to lever 287 shown in Fig. 13 and each having right-angular terminals 289 and 290 as shown in dotted lines in Fig. 12, and carrying the U-bar 210, the right-angular ends 271 and 272 of which bar are pivotally connected to the cross-bar 273 of the yoke 280. The forwardly projecting inclined side 274 of each V-member 211, lies directly in the path of the pointed ends of the inwardly pushed pins 71, whereby, as drum 47 rotates such a pin will, as said pin comes to the member 80, ride the incline 274 to the heel or apex 275 thereof, thus raising an arm 281 which arm, through its connecting link 276, in turn raises one end 277 of a lever 278 fulcrumed at 279, and forces down its arm 280, (Fig. 10) the extreme end 281 of which projects through an eye 282 of a controller arm 283 which is connected to a station selector arm 284. The end 281 contains a spring 285, (the other end of spring resting in said eye) and is normally held at the upper end of said eye by said spring. The arm 283 is pivotally mounted at its end 280, and the member 283 is pivotally connected thereto at 287. The extreme forward end 280 of said arm 283, is flattened and turned down at right angles and is normally held raised above the periphery of a disc 288. The rod 286, being held up by spring 285, keeps the arms 283 in normal position above the discs. Only on action of pin 28 against lever 278 will the arms 283 be permitted to function. Each disc 288 has one notch 289 cut in its peripheral edge in order that when the arm 283 is pressed down, through pressure of 281 by its spring 285 upon said member 283, the flattened finger 286 will drop into said notch, and through means presently to be mentioned, will stop the rotation of the shaft 284, upon which the disc 288 is freely held by an adjusting clamp-hub 292.

The disc 288 represents the radio broadcasting stations, as indicated on the station dial 78 by indice 168. As the shaft 284 rotates in synchrony with the regular radio dial 297, as will later appear, the disc 288 may be changed to represent some other stations simply by loosening its clamp-screw 293 to loosen the disc from its shaft and holding the disc in the position shown in Figure 8, until the conventional radio receiver dial indicates one of the desired stations to be used automatically hereafter, whereupon, the screw 293 is again tightened and this part of the mechanism is again ready for use. This method is used to ad-

just permanent selected stations hereafter automatically. The station identification letters are placed on the dial 78 in relative position with the disc 288. The entire method of finding new stations for the device will later be explained. 5

Fixed to the inner end of the shaft 291, is a crank-plate 294 having a crank 295 which has pivoted to it a connecting link 296 for operating the radio receiver dial 297 through a lever 298 which is fixed to the shaft 299 of the regular radio receiver 10 dial 297, whereby, when the shaft 291 rotates, it rotates said radio receiver dial therewith; thus, as the finger 288 bears upon the periphery of the disc 288 when it drops into the slot 289, the said radio receiver dial has been rotated to a point 15 where it tunes in the station represented by the disc 288, and the finger 288 has dropped into said slot, whereby the disc 288 will be held in that position until the pin 28 on the gear 315 of the lever 214, thus releasing the bell-crank lever 213 and bringing the rod 220 up and under the arms 284, and removing the finger 288 from slot 289 on the disc 288. This action of rod 220 will again allow manual operation of the regular radio receiver dial. 20 25

Automatic volume control means

Now, in order that the machine may be adjusted to the proper volume for the selected station, there is provided a shaft 300 mounted in the frame 307, which also carries the shaft 291 (Figs. 3, 9, 10 and 11). Upon the shaft 300 are fixed a series of volume regulator members 302, which are adjustably mounted on the shaft 300 by means of set screws 303. The member 302 is provided with a foot 304 which, through mechanism presently to be explained, is adapted to drop upon a pin 289' on disc 288. This action occurs immediately after the finger 288 has dropped into the slot 289 and thereby selected the station to be brought in. Fixed to the inner end of the shaft 300 is a crank-arm 305 which carries a link 306, the terminal of which is connected to a slide 307 (Figs. 2, 4 and 8) operating in the slot 308 of a slide bar 309 having a rack 310 fixed thereto enmeshed with a gear 311 which is fixed to the conventional volume shaft 312 of the radio set, whereby, when the foot 304 is stopped by the pin 289', the rotation of the shaft 300 is stopped and with it the connecting members to said volume control shaft of the radio receiver. While the member 302 is normally freely slideable over the member 307, to permit manual operation of the volume shaft 312, however, due to the friction between the member 307 and the member 308, the member 307 will pick up the member 302 and move the same up or down as the arm 283 is raised and lowered. However, when the stop 311' on the gear 311 engages the fixed pin 289'', Fig. 21, the member 307 may continue to slide up in the slot 308, without further movement of the member 302, thus permitting complete raising of the volume control fingers or members 302. This raising action of the member 302 performs the same operation that manual control would do in turning of the volume control knob of the radio set. 30 35 40 45 50 55 60 65 70 75 80 85 90

A spring 306' fixed to the shaft 300 and to the frame member 307 normally rotates the shaft 302, so as to bring a member 302 down to engagement with a pin 289' whereby, through said rack-bar 309, the volume shaft is brought to a stop at the adjusted position to procure proper volume for the station automatically brought in. The stop 311' will always hold the gear 311 in the same stopped position with volume turned off. The 75

tension of the spring 300' is greater than the friction created at slide 307, so that the volume knob may be moved either way manually without lifting the foot 304 of the member 302 off of the pin 289'. A spring 307'', compressed between the member 307 and the nut 307' produces necessary friction for the grip or slide on the member 309.

In order to absorb any shock of action to the shaft 300 by the spring 300', I connect a piston rod 313 to the lever 305, which rod operates a piston 314 in a cylinder 315 having a pin-hole 316 in its lower end, whereby the action of the shaft 300 is gently controlled. The piston 315 is pivotally mounted as at 315' in order that it may rock with the crank-arm 305.

Mounted on the regular radio set frame is a movable disc 318, having a manually operated lever 318' to be used for seasonal volume changes as well as loud or soft volume. The regular radio receiver volume unit is mounted on the disc 318 and the unit may be partially rotated without moving the shaft 312. This lever adjustment is operated manually by the operator and affects all automatically controlled volumes. The lever 318' is held in the different adjusted positions by friction which is greater than the turning effort or the radio receiver volume knob.

The disc shaft 291 (Figs. 9 and 11) is driven by a gear 319 fixed on its outer end and through a gear 320 driven by a shaft 323. A half-gear 321 is driven by a gear 322 on a rotatable and slidably shaft 323, which shaft, in turn, is driven by a pulley 324 over which is trained a belt 325, which belt is also trained over a pulley 326 on a stub shaft 327 carried on a frame member 328 and having fixed thereto, a gear 329 in mesh with a pinion 330 on a shaft 331, also carrying the worm gear 332 driven by the worm 333. The worm 333 is part of a governor shaft 334 having flexible connection with a shaft 335 of an induction motor 336, whereby the shaft 291 is rotated through the turning of the induction motor. On the outer end of the shaft 291 is a tubular hub 337, to which the half-gear 321 is fixed, and rotates on shaft 291. Mounted on the hub 337 is a coil spring 338, one end of which spring is fixed to the frame of the device, and the other end of which is fixed to the gear 321, which spring maintains said gear in normal rest position. On the opposite side of the gear 321 is a blade spring 339, Fig. 11, which spring is fixed to the gear 321, and the head 340 of the spring is turned outward so as to engage the flange 341 of the hub of the pulley 324 in its path. 342 is a light coil spring between the frame and hub-flange 341, normally holding the shaft 323 in outward position, so as to engage its fixed pin 343 with a ratchet hub 344. When the pulley 324 is driven in one direction by the motor 336, turning gear 322 (fixed to hub 344) which meshes with half-gear 321, it raises the spring 339 in the path of the flange 341, the head 340 presses inwardly on the flange and shaft, to snap the pin 343 out of the ratchet 344, and slide over to engage the ratchet hub 345 of the gear 320, thereby driving the gear 319. The hubs 344 and 345 are held from sliding by frame members 301' and 301'', permitting turning motion only, while their shaft 323 has both sliding and turning motion. Normally the pin 343 in the shaft 323 is held by the spring 342 against the ratchet hub 344 of the gear 322, whereby, in rotating in one direction, the pin 343 will pick up the ratchet and rotate the gear 322 with said shaft 323, whereby the half-gear 321

is rotated, to bring the spring head 340 into relation with the flange 341, as above stated. When the pulley 324 is moved toward the gear 322, the shaft 323 is moved forward so that the said pin 343 releases the ratchet of 344, and engages the ratchet hub 345 to rotate its gear 320 whereby the gear 319, with its shaft 291, are rotated and move the connections to the regular radio receiver station dial. Pivoted to the gear 321 is an arm 346, having a slot 347 in which the pin 348 of a telescopic arm 349 operates. The terminal of the arm 349 is pivoted at 350 adjacent the outer end of a lever 351, and fixed on the shaft 300 whereby when the gear 321 rotates, the shaft 300 will be rotated about ninety degrees to raise the control member 352 to an upright position, and entirely out of engagement with the discs 289. When the volume control member 352 has reached this position through operation of the half-gear 321, the governor 353 acting on the shaft 334 has expanded and carried forward its terminal collar 354, and with it the arm 355 of a lever 356, which lever has another arm 357 which engages the spring 358 on the gear 321, and as this spring passes the arm 357, compressing the spring until the head 359 of the spring has passed and springs out over the terminal of the member 357, the gear 321 is held temporarily against reverse action. At the time the arm 357 is engaging under the spring 359, the arm 360 of the lever 356 connected to 361 at the lower end of a lever 362, is moving said lever upon its fulcrum 363 in order that its other end 364 will push forwardly upon the link 365 which is connected to 366 to a bell-crank lever 367, the terminal of the arm 368 of which is operated into the path of a pin 369 on the extreme end of the lever 351, whereby the member 352 is also held against reverse movement.

Upon the electrical cutting off of the motor 40 336, the action of the governor will cease, whereby the member 352 will be moved out of engagement with the spring 358 on the gear 321, permitting this gear, through the action of the spring 338 to reverse itself; yet the member 352 45 is still momentarily held in raised position through said bell-crank arm 368, whereby the spring head 340 disengages the flange member 341 to permit outer movement of the shaft 323. The telescopic arm 349 is at this time allowed to 50 extend itself as the half-gear 321 falls to normal or rest position. Just prior to the release of said spring head 340 from the flange 341, a primary kick occurs through the action of a kick member 370 against the inner end of the shaft 323, the 55 connections of which will be presently explained.

At this time the governor further expands to drive the collar 354 toward the motor to operate the member 356 to move its arm 360 to operate the lever 362 pulling rearward the rod 365 operating the bell-crank 367 to release its arm 368 from the pin 369, permitting the shaft 300 to fall to allow the arms of unit 352 to also fall, whereby one of the arms 302 engages a pin 289' on one of said discs 289.

As the shaft 300 falls, it carries with it a lever 371, moving said lever in the path of the end 372 of a lever 373 having a hump 374 which presses against the flange 341, and there completely kicks out the shaft 323 bringing the pin 70 343 completely out of engagement with the ratchet of the hub 345, the shaft now standing in neutral position. A further downward movement of the arm 371 disengages the member 372 which is pivoted at 375 and which lever is again 75

thrown into its normal position by means of its spring 376.

The link 365 is provided with a centrally located annular groove 377 which is engaged by an arm 378 of a bell-crank lever 379 pivoted at 380, the outer arm 381 of said bell-crank lever having pivotal connection at 382 with a link 383 having a rubber bumper 384 on its free end, said bumper normally standing in the path of one of the stops 385 and 385' on the crank-plate 294, whereby said plate is kept from stopping on dead-center when operating the radio receiver dial manually. When the link 365 is again moved forward (by the action of the induction motor), the bell-crank lever 379 will draw the bumper 384 out of the path of said stops 385 to permit complete rotation of the crank plate 294. Located on side of frame 301 and behind rubber bumper 384, is an electrical switch controlling the circuit to the volume unit 317 of the radio set. When the bumper 384 is drawn out of the path of the stops 385 and 385', said bumper opens the electrical circuit supplying current to the volume unit 317. Therefore, there will be no radio noise whatever, as the radio receiver dial is moved from station to station automatically.

Fixed on the upper surface of the arm 360 is an upstanding bracket 386, to which is connected a link 387, engaged with the arm 388 of the bell-crank lever 389, fulcrumed at 390 and having its arm 391 bearing against the plate 392 depending from the lever 361, which, as before stated, is fixed to the shaft 300, whereby the pressure of said arm 391 against the plate 392, will move 35 the shaft 300 sufficiently to disengage the foot 304 from the pin 289' at the time the motor 336 first starts into operation. In order that the unit 352 will be slid over to a position to allow one member 302 to fall on a pin 289' (to which 40 the member 302 will rest on a pin 289' of a certain station disc), I provide a plate 393, mounted on the frame 301, and having a turned end-face 398, against which the arm 397 slides, on only its downward movement (when and if pin 289' 45 has been moved out from under the foot 304) to slide the shaft 300 and its parts outwardly so as to clear the pins 289' if and when the radio receiver dial is manually operated. This falling of the unit 352 happens only when the radio receiver dial is moved in either direction, (after having been set automatically) causing the pin 289' to slip out from under the foot 304 of the part 302. On upward movement of the unit 352, the arm 397 is rising in another path than that 50 in which it fell, where, on its nearly completed travel upward, it strikes the V-arm 396 of V-member 395, causing the arm 397 to slide again back to a position to be ready to allow the members 302 to strike a pin 289' in the falling action. 55 Fixed to the frame (Fig. 21) is a bracket 399, carrying a ball and socket 400, the ball of which engages one of the grooves 401 or 401' on the shaft 300, whereby said shaft is held against accidental movement in either direction. 60 When a pin 71 moves under a V-member 261, raising the arm 277 through the link 276, and in turn pressing down the terminal 281, on the spring 285, the action is to force the member 286 into the slot 290 on the disc 289, (Figs. 9 and 10) 65 whereupon the lug 402 on said member 286 will bear down on the edge 403 of a switch-plate 404 having end pins 405 and 406, upon which it is pivotally mounted. This action causes a lever 407 on the member 404 to force down a link 408 70 connected to the end 409 of a lever 410 fulcrumed 75

at 411, in turn forcing up the short end 412 of said lever to raise the link 413, which actuates a brake 414 on the brake-drum 415 on the shaft of the motor 336, whereby the motor shaft will be stopped almost simultaneously with the cutting 5 off of current to the motor, in order to quickly stop its action on the governor 353.

In order to again bring the member 404 back to its normal position, I provide a link 416, one end of which is pivoted at 416' to the lever 40, 10 (Fig. 17) and the other end of which is connected to the arm 417 of a bell-crank lever 418, (Fig. 10) to the other arm 419 of which is attached a link 420, having its end 421 flattened and slotted to form a fork 422, which rides a pin 423 on the 15 U-shaped lever 424 pivoted to an inverted U-bracket 425 fixed to a frame member 426. Fixed to the end of the member 404, (Fig. 10), is an arm 428 having a fork-end 429, also engaging the pin 423, whereby when the link 420 operates 20 the lever 424, said lever also swings the arm 428 to again raise the switch-plate 404 to normal position. Attached to the bracket 425 is a coil-spring 430, the other end of which is attached to the head of the U-lever 424 whereby said 25 switch-plate 404 will be held under tension in either of its positions. Carried on the member 404 are a series of leaf springs 431, the free 30 ends of which seat under the lugs 402 of members 283, whereby, if one of the terminals 281 is depressed and one member 283 pushed down, moving the edge 403 from under the lugs of all other members 283, said springs will hold the idle members 283 raised against gravity. Another function of these springs is to assist in raising the 35 edge 403 of the member 404 to lower its edge 403. A stop 433 is provided to limit movement of the U-member 424. Pivoted above the volume control member 352, is a bar 434 having fingers 435 which may be turned in or out of the path of the 40 members 302, whereby, if in the path of the turned-up head 304' of said members, the bar will be tilted up to break a circuit, disconnecting the aerial from the radio set. This is done when a 45 local or nearby station interferes with proper reception of automatic programs, (corresponding with the "Local-Distance" switch on most conventional receivers). This bar 434 is provided on one end with an arm 434' so positioned that when the bar normally swings down, by gravity, 50 the spring switch-member 435 will close the aerial circuit to the radio receiver.

Electrical circuits and visual signal means

Taking up the electrical circuits which control 55 the machine, (Fig. 23) it will be noted that there are two principal circuits 431 and 438, and two minor circuits 433 and 440. Taking up circuit 431 and tracing it through from the junction block 441, through which service energy is received from the positive and negative wires 442 and 443, from the post 444 on the block 441, the wire 445 leads to the motor 5, through the motor, back through the wire 446 to the negative post 447; thus, the synchronous motor 5, which 60 controls all of the timing mechanism heretofore described, receives its energy. The second circuit 438 starts at the post 444 leads through the wire 448 to the regular radio receiver switch 449, through which switch the automatic action of 65 the entire machine is also controlled, as said switch 449 must be closed to pass current to the other switches to be presently referred to. From the switch 449, the wire 450 leads to a binding post 451, and thence through the conductor 452 70

of the combined manually and automatically controlled switch 483 from which current passes to a switch member 454 to post 455 and thence to the radio set through the wire 456 and return 5 to the negative post 447. This circuit to radio set is controlled by a manually operated lever 458' as part of a bell-crank lever 458, a link 459, another bell-crank 460, a link 461, a third bell-crank lever 462, and a link 463, which last 10 link is attached to the non-conductor button 464 which, in turn, is adapted to push the member 454 into contact with the member 452, closing complete circuit to the radio set. Attached to the post 465 is another conductor switch member 15 466 pushed by the non-conductor end 467 of a push-rod 468, which rod is controlled by the crank member 469, pivoted at 470 and 471. The member 469, terminating at one end in a crank 472, has connected to its arm 472, a link 474 20 which, in turn, is connected to a lever 475 pivoted at 476, and to the end 477 of which the link 468 is connected. A coil spring 470' at 470 assists in holding the bar 469 up under the terminals 281 of the levers 280. This arrangement provides means for closing all three of the 25 conductors 452, 454 and 466 upon one another, automatically turning on the radio set. From the post 465, a wire 478 leads to a post 479 on the conductor bar 480 carried by a peculiar shaped 30 insulator cam 481, thence through the conductor arm 482 to a switch 483. The terminal 484 of a conductor spring is so bent as to project normally above the periphery 485 of the arm 486 of said cam 481 and lies in the path of an insulated pin 487 on the gear 11, whereby the switch 483 is closed for a short period once with each complete revolution of said gear. From the switch 483, the conductor spring 488 leads to a post 489, thence by a wire 490 to a switch 491, 40 which has previously been closed by an arm 492 (Fig. 22) on one end of the switch-plate 404. From the switch 491, a wire 493 leads to the induction motor 336 and from the motor a wire 494 leads to negative post 447, thus, completing the circuit. The switch 483 closes the circuit to start the motor and switch 491 again opens the circuit to stop the motor after it has performed its duty, heretofore explained.

As the pin 487 passes over the arm 486 of the cam 481 which is pivotally mounted at 485, said arm as before stated, being in the path of said pin, tilts the member 481, which raises the outer end 496 of a switch 497, which comprises conductors 498 and 499, spaced apart at the member 481 by an insulator 500. As the said end 496 is raised, it is brought into contact with an insulated cam 501, on the insulated cam-wheel 502. From a post 503 on the member 499 a wire 504 leads to a switch 505 from which a wire 506 leads to a light 507, from which light another wire 508 leads to the negative post 447, thus completing the circuit to said light. When the end 496 is raised through the action of said pin 487, on the member 481, the member 499 is brought into the path of the cam 501 to close the switch member 499 against the member 498 for a short period. As the pin 487 passes further out on the arm 486 of the member 481, the said switch end 496 is raised still higher to engage the member 502. However, when the cam 501 has first passed out of engagement with the switch member 499, the circuit is again opened momentarily to break the light circuit, but when raised still higher to the member 502, the switch is again closed and held closed until the mechanical operations

motor 336 have been completed, whereupon, the pin 487 is passed off the portion 484 of the switch member 488, opening the switch 483 but still momentarily holding the switch 487 in engagement with the cam-wheel 502. Then the pin 487 passes off the extreme end of the arm 486 letting the switch 487 drop out of contact with the cam 501, breaking the circuit to the light 507. A spring attached to the frame of the device, bears normally upon the heel 509 of the member 481 whereby it is held in normal position. When a pin 71 in the drum 47 is depressed and moves into the path of one of the V-members 211, actuating said member, and through it the terminal 281 of the arm 280, the bar 469 is depressed, operating the crank 472 (Fig. 8) which has attached to its lower end an insulator 510 having fixed thereto a switch member 511, of a switch 505, whereby said switch is closed and opened. This action, of course, occurs prior to 20 the automatic operation of the device to bring in a predetermined radio program, as indicated through the particular pin 71. This action of the bar 469 on the switch 505 closes the circuit before the motor 336 comes into action, allowing the switch 487 to regulate the signal light.

General observations

In certain cases it may be desirable that the device be operated for a certain number of hours 30 during the day or night, and vice versa; therefore, in order that this may be accomplished, I have provided a dial 24 (Figs. 1, 4 and 6) mounted upon a slidable shaft 23, normally held out by a spring 514. The dial 24 is so arranged as to 35 show the non-operating sections in black, and the light sections represent the automatic playing periods.

In this particular machine the light section includes seven A. M. to ten P. M. and the dark section the balance of the twenty-four hours. 40 Approximately two-thirds of the day of 24 hours is used for automatic operation; hence, only about two-thirds of the total three hundred and thirty-six cogs 45 are needed on the drum 47. If the time for automatic playing were reduced to one-half of a twenty-four hour day, whether consecutive or divided periods, then only one-half of the cogs 45 would be necessary. So we see that the shorter the automatic periods of playing time, the lesser number of cogs needed. As the pins 50 71 are the exact number of half hours to play, and as these are reduced in number around the circumference of the drum, the drum may be made smaller; likewise, proportionately, if the drum had the complete number of cogs in its 55 ring-gear, (three hundred and thirty-six) then the automatic playing time would be the full twenty-four hours of a day for seven days or a week. No dark sections on any dial would be 60 necessary. By the following method I will show how I stop the drum 47 from its rotation when non-automatic periods of time arrive. In this way, I keep the drum on a weekly revolution schedule. Of course, the drum must have a blank 65 transverse row 53 when the drum is at rest at non-operating periods, in order to keep the presser feet 211 at rest.

On the inner end of the shaft 23 is mounted fixedly the gear 15, operated through the pinion 70 14, as herein before explained. Also fixedly mounted on the inner terminal of said shaft, is a cam wheel 515, the cam 516 of which travels in the path of a projection 517 (Fig. 17) on an arm 518 fixed to the pawl 43, whereby, when the 75

end 516 of said cam reaches the pin 517, and is traveling in the path thereof, the terminal 44 of the pawl 43 is held out of engagement with the teeth 45 of the internal ring-gear 46 on the drum 47. This cam arrangement allows the drum to stand stationary, while the twenty-four hour dial, with the cam, revolves through its dark or non-automatic section. This action continues until after the end 520 of said cam has passed beyond 10 said projection 517, whereupon, the machine will operate continually until the cam end 516 again reaches said pin. Through this arrangement, the machine may be automatically stopped from operating through any desired period of the day or 15 night by adjusting the cam-wheel 515 upon its shaft, or adding more cams 516 to the wheel 515 and adjusting to non-automatic periods of time.

Through the above arrangements it will be apparent that a series of programs may be set running through the active broadcasting periods of seven consecutive days, and that the drum may be given step-by-step movement through each of 20 said active periods starting with the day when the programs are set and to the end of the seventh 25 day thereafter. Furthermore, that by rendering the cancelling mechanism inoperative the machine will operate continuously from week to week through an indefinite period of time to repeat programs set for the same times and stations 30 over many weeks in succession.

Fixed on the outer end of the shaft 21, upon which the gear 11 is mounted, is a disc 521 having a cut-out 522 in the periphery thereof, (Figs. 6 and 7) against the inner face of which disc the shoulder 423 of the switch member 466 normally rides until the member 467, pushes thereagainst, which action will cause the switch member to 35 pass through the cut-out 522 against the switch members 454 and 452 and be held thereby on said disc 521 until a complete rotation thereof, and at 40 the time the cut-out again reaches the member 453, the link 468 has been withdrawn by means previously explained, these means being the moving of the drum 47, when the pin 71 has gone on 45 past the presser-feet 211, to be "cancelled" or pushed out mechanically by the U-bar 212, or the pin retained by the action of the wedge 163 under the foot 165 from the button 164. So by the time 50 the cut-out has made its complete revolution, the pin 71 has passed, and no part of the unit 88 is in action, thus allowing the switch member 466, which is formed of a leaf-spring, to return, through its spring action, to the inner side of 55 the disc where it will be kept out of contact with the other members 454 and 452 of the automatic switch 453, until again operated upon by the link 468 and the said cut-out 522 has been reached, this latter operation being caused by another raised pin 70.

From the above description it will be apparent 60 that the circuit 440 and the circuit 430, including the signal light, are first closed and operate to turn on the radio and turn on the signal light before the circuit 430 is closed to operate the motor for actuating the tuning and volume control means. This necessarily is in advance of the tuning-in of a radio program. It will also be apparent 65 that if two pins 71, or actuators, representing immediately contiguous time periods are set, that the member 523 will be held from passing through 70 the cut-out portion 522 to continue in circuit contact with the disc 521, whereby the radio circuit will continue to be closed until such time as no program is set for an immediately succeeding 75 period, in which case the member 523 will fall

through notch 522 and the radio set be turned off.

Fixed on the extreme outer end of the shaft 21 is the minute dial 22, previously referred to. This dial, through the train of gears 12, 13, 14, 15 and shaft 23 upon which the latter gear is fixed, operates with the twenty-four hour dial 24. The gear ratio between these two dials 22 and 24 is forty-eight to one. In order to set the dial 24 to time, said dial is divided into hour and half-hour markings, and a fixed indice 524 is fixed to 10 the frame, said indice being carried by an arm 525 also having indice 526 co-operating with the minute dial 22, which is marked in minutes and half-minutes. By pushing inwardly against the knob 23' and against the tension of the spring 15 314, this slide movement of the shaft 23 and gear 15 will slide the gear 15 out of mesh with the pinion 14, allowing the shaft to revolve freely, and with it the cam-wheel 515 which is set fixedly with the dark section of the dial 24. The gear 15 will mesh with the pinion 14 when the dial is turned to indice setting, and the inward pressure released.

Operation of the device

In operating the device it is first necessary for the user to determine what radio broadcasting station or stations he desires to bring in at various times, for certain programs. In order to do this, the machine must be set for these stations, and therefore, all of the discs 289 must be set to accord with the stations desired, which stations must also be designated upon the dial 70, the location on the dials being relative to the position of each disc.

In order to get a desired station adjusted for future use, a disc 289 is loosened from the shaft by its clamp-screw. Then hold the disc by its notch 290, by pressing on the finger-plate 230, and pressing down on the member 283 manually, in turn forcing the finger 230 into a notch. This will hold the disc from revolving, while the regular radio receiver dial 297 is used to find the favored station or stations in the customary manner, (radio receiver tuned-in). Then the disc is again clamped to its shaft, completing the setting of the machine for this particular station. Now we take the location of said station on the radio receiver and designate it by its identification letters, according to which disc has been used, upon the station recording dial 73. The location of this station must be designated on the dial 70, in accordance with which disc has been set for it. Example—first disc—first location on dial 70; fifth disc—fifth location—etc. It may be stated here that the dial 70 is divided into as many sections as there are discs 289, and each of said divisions are numbered in accordance with the position of said discs on the shaft 291. This completes the location of a station on the machine. Now in order to regulate the volume for the particular station or stations so located, the member 352 is allowed to drop against the spring tension by which it is held in order that terminal 304 may engage the pin 289' on the disc being adjusted. As the member 352 falls to its position to engage said pin, the link 305 operates with it to move the rack-bar 309, operating the radio receiver volume shaft 312, whereby the proper volume for the station, now designated on 75 the radio receiver dial is obtained, by adjusting set-screws 303. This completes the adjustment of the machine for desired stations to be later brought in or tuned-in through automatic control.

Now, in order that the user may set the machine for desired programs on the stations now designated on the station-dial 78 above referred to, he operates the knob 106, which in turn, through a train of gears, above explained, operates the panel 129, and indice 130 to the day on which the desired program is broadcast; then, turn said knob 106, with indice 108, to the proper hour on dial 110, upon which time the desired program will be broadcast. After this is accomplished, the station locating knob 134 is rotated until its indice 135 indicates the station on said dial 78 that is to broadcast the desired program. Either of the two knobs 106 or 134 may be used first to select a program, as the same pin 11 will be located in either case. Now the only remaining step is for the user to press down the finger-plate 148 of the lever 150, which operation, through said lever, operates the push-pin 84, which pushes in one of the pins 11, on the drum 41, which completes the recording of the station, day and hour of the desired program. As many of these programs as desired may be recorded at any time as far as one week in advance, whether the machine is in operation or idle, as desired. Then, as the machine operates upon exact time, through its motor 5, as one of the pins, which was punched in, passed under a V-member 211, which in turn operates the levers 218 and members 283 and 284, this causes the finger 288 of the latter to fall into the slot 280 of the disc 289, as it rotates through the operation of the induction motor 336, as herein before explained. The disc is held in its position through said finger, for the period designated by the signal-light 501, during which period the machine cannot be manually changed, but after which period the finger 288 is again released through the mechanical raising of the bar 220, and if the program about to be played should not be wanted, the radio receiver dial may be manually changed. During the time of the program being played and before its termination, through automatic operation of the machine, further programs of said station may be continued if the knob 134' is pushed in, in order to move the wedge 183 under the stop 185 on the link 174, preventing pushing out of the pin 11, in order that the machine will again pick up the same program at the same hour the following week. If the knob 134' is manually pulled outwardly, then the program being played will be automatically cancelled, by the action of the pin 28 (on gear 11) through mechanical means, by pushing out the pin 11. The pushing in of the knob 134' merely keeps the pin 11 from leaving its operating punched position, saving the recording of the same program for the following week.

There is the very highest advantage in the arrangement above referred to whereby selected programs will be brought in at the same times and over the same stations from week to week for indefinite periods of time. This is in fact one of the most important advantages of my radio program selector. It is a fact that a large proportion of the most important and interesting radio programs for both day and evening reception are in series continuing on a certain day or days at the same hours and over the same stations from week to week. Most radio listeners are particularly interested in hearing the successive numbers of these continuing programs. It is true that in literally millions of instances listeners are disappointed because they have forgotten to tune in the radio for the appropriate time and station in

which they are interested. My invention makes it possible, through day after day and week after week, to bring in the desired programs in continuation of sets or series of programs without any attention or requirement to remember the time 5 of coming in of said programs on the part of listeners.

It may again be stated at this point that when stations are preselected on the machine for certain programs, that each one of these programs 10 will be picked up and tuned-in, and the proper volume control adjusted, as they are broadcast from week to week by their particular stations. It may also be stated that the automatic operation of the machine may be cut out altogether if 15 desired, so that manual operation may be had to pick up programs and stations from time to time, not recorded on the machine, and that such manual bringing in of other stations and programs will not, in any way, interfere with future 20 operations of the machine to bring in programs recorded thereon.

As the cogs 45 are moved, one at a time, through the pawl member 44, once every thirty minutes, through the timing of the machine, and as the 25 gear 122 is in mesh with said cogs, said gear 122 is moved by the movement of the drum 41, one cog each thirty minutes, and with the movement of said gear, its tubular shaft 108 is rotated, upon the outer end of which is fixed the gear 121, to 30 which the dial 110 is also fixed, said dial being moved in relation to the indice 248, whereby each exact half-hour period is indicated on said dial, day and night periods also being indicated on the same dial through light and shaded portions 35 thereof, and as the said hour dial 110 is geared to the dial 78, at a ratio of seven to one, the former dial will rotate seven times to one rotation of the day dial. The day dial makes one complete revolution in one week, the same as the 40 drum 41.

Having now described my invention, that which I claim to be new, and desire to procure by Letters Patent, is:

1. In a radio program selector, a movable member 45 carrying seven sets of actuators each set of actuators adapted to control tuning in of radio programs from any predetermined selected one of a plurality of sending stations at predetermined selected times and for predetermined selected 50 intervals over an active period of time less than twenty-four hours, the entire seven sets covering the active radio broadcasting periods for an entire week, means to set selected ones of said actuators in each of said sets for an entire week's program, 55 means to move the member a single step at the ends of said intervals within any of the active periods of time in any of said seven sets, and means rendering said last-named means inoperative to move the member during the part of 60 any twenty-four hour period not included in said active radio operating periods.

2. In a radio program selector, a movable member carrying seven sets of actuators with means 65 cooperating with each actuator when the member is moved a single step so that each set is adapted to bring in radio programs from selected ones of a plurality of sending stations at selected times and for predetermined intervals within a single twenty-four hour period, the seven sets covering 70 the active radio broadcasting period for an entire week, means to set selected ones of said actuators in each of said sets, a continuously operating power device, means operated by the power device to move the member a single step at the ends 75

of said intervals within the active broadcasting periods of each day, and means for throwing said last named means out of action during the inactive broadcasting periods of each day, whereby 5 a given set of selected programs may be repeated week after week indefinitely without resetting said actuators.

3. In a radio program selector, a movable member carrying a multiplicity of actuators for controlling the tuning in of radio programs from any predetermined selected one of a plurality of sending stations at predetermined selected times and for predetermined selected intervals over an active period of time less than twenty-four hours, 10 means to set selected ones of said actuators, means to move the member a single step at the beginnings of said intervals within the first-named period of time, and means rendering said last-named means inoperative to move the member 15 during the part of said twenty-four hour period not included in said active radio-operating period.

4. In a radio program selector a movable member carrying a multiplicity of actuators arranged 20 thereon in transverse and longitudinal rows, the transverse rows representing consecutive time periods for a week of seven days and the longitudinal rows representing separate stations, means to set a series of said actuators for programs at succeeding different time periods and over any or all said stations for the seven consecutive days of an entire week, a synchronous power device operating continuously over the entire weekly period, means operated by the power 25 device to move the movable member a single step from row to row of actuators at the beginnings of predetermined time periods, means successively engaged by said set actuators at the times and for the stations so set throughout the entire 30 weekly period when the member is so moved, and means set in operation by the last-named means at the ends of said time periods to turn on, tune in, and adjust volume control for a selected program.

5. In a radio program selector, a movable member carrying a multiplicity of actuators each adapted to be set for time and station, means associated with the movable member to be engaged by said actuators when it is moved a single predetermined step, means for moving the member a step at a time, means rendered operative by engagement of an actuator with the said associated means to cause selection of a program for the time and station called for by the actuator, a signaling means, and means rendered operative by the said actuator to operate the signaling means to show that a program will soon be tuned in.

6. In a radio program selector, a drum open at 60 one side bearing a multiplicity of actuator pins arranged in circumferential and transverse rows, means to move said pins radially inward to project within the interior of the drum in position to actuate for selected times and stations, means 65 for moving the member a single step at pre-selected times, means extending through said open side within the drum and in the path of inwardly-projected set pins to be engaged by a set pin as the drum is moved a single step, and means 70 rendered operative thereby to turn on the radio receiver and bring in a preselected program.

7. In a radio program selector a movable member carrying a mutiplicity of actuators, means to set selected ones of said actuators to actuate 75 for selected times and stations, a constantly op-

erating power device and connections for moving the member a single step at the beginnings of predetermined time periods, means engaged and set by said set actuator when the member is so moved, and means set in operation thereby at the 5 end of the time period to turn on the radio and tune in a program for the next succeeding time period.

8. In a radio program selector, a movable member carrying a multiplicity of actuators for controlling the tuning in of radio programs at predetermined successive time intervals, means to set selected ones of said actuators, means to move the member a single step at the beginning of said intervals, means set thereby for turning on 10 the radio receiver at a time before the end of said interval, means for maintaining said radio turned on through the next succeeding interval, and means whereby if a succeeding program has been set the radio is maintained turned on through the 15 succeeding time interval.

9. In combination with the tuning means and volume control means of a radio receiver, power means, means adapted to be operated by said power means to operate the tuning means to 20 move it back and forth throughout its complete tuning range, means whereby the power means will set the volume control means of the radio at one of the limits of its possible positions, means to cause the power means to operate the 25 tuning means, means corresponding to a selected radio station automatically operative to stop operation of the tuning means and disconnect the power means therefrom at a point corresponding to the tuning position of the selected 30 station, and means effective upon disconnection of the power means to release the volume control means to permit it to move from the extreme position where it has been moved and held to a proper volume setting position, and means so to 35 move it.

10. In a device of the character described, a movable member having an extended wall, a multiplicity of pins extending through said wall and lying in transverse and longitudinal rows and 40 adapted to occupy normally non-operative or operative positions thereon, a projector member and means to position it to overlie a pin in any longitudinal and transverse row, manually-operable means to operate the projector in any of its 45 positions to force a selected pin from its normal non-operative to its operative position, a second projector overlying a transverse row of pins of which one may be in its operative position, and manual means for operating the second projector 50 to restore to non-operative position any pin in operative position in a transverse row before a program represented by said operative pin has 55 been begun.

11. In combination with tuning means and the 60 operating electric circuit of a radio receiver, means including a power device for automatically operating said tuning means to move it back and forth through its complete tuning range, means selectively set and rendered active cooperating 65 with said operating means for positively stopping operation thereof at a selected point in said operation corresponding to a selected one of a group of stations, and means associated with the means for actuating said operating device for turning 70 on the electricity to said electric circuit at a time sufficiently advanced from the operation of said stopping means to permit the radio tubes to warm up sufficiently for action, whereby said selected station is positively and precisely tuned 75

in and will give reception and reproduction of a program at its commencement.

12. In a device of the character described, a movable member having an extended wall provided with a plurality of holes through its wall, said holes lying in longitudinal and transverse lines, grooves extending along the sides of said longitudinal rows of holes, wires in the said grooves having portions overlying opposite segments of the circumferences of said holes, and pins having axially spaced notches defining operative and non-operative positions positioned in the holes and engaged by the wires, whereby the pins may be moved through the said wall and detained by the wires in operative or non-operative position.

13. In a device of the character described, a movable member having an extended wall provided with a plurality of holes through its wall, said holes lying in longitudinal and transverse lines, grooves extending along the sides of said longitudinal rows of holes, said grooves having walls beveled away from the rows of holes, wires in the said grooves having portions overlying opposite segments of the circumferences of said holes, said wires adapted to slide up the beveled sides of the grooves, and pins having axially spaced notches defining operative and non-operative positions positioned in the holes and engaged by the wires, whereby the pins may be moved through said wall and detained by the wires in operative or non-operative position.

14. In combination with a radio receiver and its case, a movable member within said case having an extended wall, a multiplicity of pins extending through said wall and lying in transverse and longitudinal rows and adapted to occupy normally non-operative or operative positions thereon, a carrier and a projector member thereon held to overlie one of said pins, means at the front of the case and connections to shift the carrier member longitudinally to cause the projector to overlie any pin of a longitudinal row, means at the front of the case and connections to shift the carrier transversely to bring the projector over any pin of a transverse row, and means at the front of the case to operate the projector in any of its positions to force a selected pin from its normal non-operative to its operative position.

15. In combination with a radio receiver and its case, a movable member within said case having an extended wall, a multiplicity of pins extending through said wall and lying in transverse and longitudinal rows and adapted to occupy normally non-operative or operative positions thereon, said pins along said longitudinal rows being positioned to actuate for time intervals and the pins along the transverse rows being positioned to actuate for station settings, a carrier and a projector member therein held to overlie one of said pins, means including a manually-operable member at the front of the case and a time-indicating scale associated therewith to shift the carrier member longitudinally to cause the projector to overlie any pin of a longitudinal row, means including a manually-operable member at the front of the case and a station-indicating scale to shift the carrier transversely to bring the projector over any pin of a transverse row, and means including a manually operable member at the front of the case to operate the projector in any of its positions to force a pin from its normally non-operative to its operative position.

16. In combination with a radio receiver and its case, a rotatable drum within said case having an extended cylindrical wall, a multiplicity of pins extending through said wall and lying in transverse and circumferential rows and adapted to occupy normally non-operative or operative positions therein, a shiftable projector member means including manually-operable devices at the front of the case to shift the projector circumferentially and transversely to position it above any pin in any transverse and circumferential row, and means including a lever system and a plunger operative along the axial center of the drum to operate the projector in any of its positions to force a pin from its normally non-operative to its operative position.

17. In combination with a radio receiver and its case, a rotatable drum within said case having an extended cylindrical wall, a multiplicity of pins extending through said wall and lying in transverse and circumferential rows and adapted to occupy normally non-operative or operative positions therein, a shiftable projector member means including manually-operable devices at the front of the case to shift the projector circumferentially and transversely to position it above any pin in any transverse and circumferential row, means including a lever system and a plunger operative along the axial center of the drum to operate the projector in any of its positions to force a pin from its normally non-operative to its operative position, and means cooperating with said lever system to center the projector above the selected pin as it is actuated to project the pin into operative position.

18. In combination with a radio receiver and its case, a rotatable drum within said case having a cylindrical wall, a multiplicity of pins extending through said wall and lying in transverse and longitudinal rows and adapted to occupy normally non-operative or operative positions thereon, a carrier and a projector member thereon mounted to rotate on a supporting shaft lying along the axis of the drum, means including a manually-operable member at the front of the case to rotate the carrier to bring the projector to overlie any pin of a longitudinal row, and means including a manually-operable member at the front of the case to shift said axially centered support for the carrier endwise along the axis and within the hub of the drum to bring the projector over any pin of a transverse row.

19. In combination with the tuning and volume control means of a radio receiver, means for actuating said tuning means including a rotatable member having a multiplicity of discs thereon and rotatable therewith, each provided with a notch positioned thereon relative to the position of said member at a point corresponding to the tuning position of the member for a given station, and each provided with a laterally extended pin adapted to be positioned as a volume control stop when rotation of the disc has been stopped, devices adapted to be set singly for time and station to be automatically actuated into position to engage in a selected one of said notches and terminate the rotation of said member when it has reached the tuning position of the selected station, a member having operative connection with the volume control means carrying a plurality of detents each corresponding to a selected radio station and each set so that when it engages a positioned pin on the disc it will move the volume control means to set the proper volume for the corresponding station, means for render-

- ing the first-named means operative to rotate the member and discs and actuate the tuning means and at the same time to set the volume control means at one of its limits of position, 5 and means thereafter to move said volume control means so that a detent thereon will engage the positioned pin on the selected disc.
20. In a radio program selector, a movable member carrying a multiplicity of actuators 10 adapted to be set to actuate for time and station, means associated with the movable member to be engaged by said actuators when it is moved a single predetermined step to effect selection of a program, a synchronous power device, a 15 rapidly moving member constantly driven in a timed manner by said power device, a contact element, a slowly moving member synchronously driven in relation to the rapidly moving member for introducing the contact element into the path 20 of the rapidly moving member at the expiration of a fixed period of time, and means connected with said contact element for positively moving the first-named member a single step.
21. In a radio program selector, a movable member carrying a multiplicity of actuators 25 adapted to be set to actuate for time and station, means associated with the movable member to be engaged by said actuators when it is moved a single predetermined step to effect selection of a program, a synchronous power device, a 30 pusher member constantly rotated thereby at a constant speed of one minute for each rotation, a second member constantly rotated by the power device at a rate of one revolution in 35 thirty minutes, means actuated by said second member to be introduced thereby into the path of the pusher member at the expiration of a fixed period of time having operative connection with the first-named movable member, whereby 40 said first-named member will be moved a single step every thirty minutes.
22. In a radio program selector, a rotatable drum carrying a multiplicity of pins adapted to be set to actuate for time and station, means in 45 the path of said actuators when so set to be engaged by the actuators when the drum is moved a single predetermined step to effect selection of a program, a synchronous motor, a wheel constantly rotated thereby at a constant speed of one minute for each rotation, a second wheel 50 constantly rotated by the motor at a rate of one revolution in thirty minutes, a pin on the minute wheel, a plunger actuated by said second wheel to be introduced thereby into the path of the 55 pin at the expiration of said thirty minutes, and means connected with the plunger having operative connection with the first-named movable member whereby said first-named member will be moved a single step every thirty minutes.
- 60 23. In combination with a radio receiver, movable station selecting means comprising a plurality of actuating elements each of which represents a station and time, automatic means for preventing the normal motion of said station selecting means over predetermined periods of 65 time, means for setting the tuning means of the radio receiver including a rotatable shaft adapted to be detained in a position determined by one of the actuating elements at the time represented 70 by the said elements, means associated with said last mentioned means for adjusting the volume of the selected stations, and means for turning on the current to the radio receiver in advance of the tuning of the receiver to a particular station.
- 75 24. In combination with a radio receiver, a

rotatable drum provided at its periphery with actuating elements movable to operative or non-operative positions, manually operable means for moving desired elements to operative positions, manually operable means for moving said elements to non-operative positions, means actuated by said elements for tuning the radio receiver to a desired station at a predetermined time, automatic means for moving an element to non-operative position after it has functioned to 10 tune the receiver, and manually operable means for preventing, if desired, the action of said automatic means.

25. In combination with a radio receiver, a drum rotatable in a timed manner, a plurality 15 of pins movable through the cylindrical wall of the drum to operative or non-operative positions, the pins being arranged in circumferential columns which represent stations and in transverse rows which represent times, means for moving 20 a desired pin to operative position, means actuated by pins in operative position whereby the stations represented by the pins are tuned in at the times represented by the pins, manually operable means for moving any pin in a particular 25 transverse row to non-operative position before the last mentioned means are actuated, automatic means for moving any pin in a particular transverse row to non-operative position after the pin has functioned to actuate the means for 30 tuning the radio receiver, and manually operable means for preventing, at will, the action of the automatic means.

26. In combination with a radio receiver, a 35 rotatable drum carrying at its periphery a plurality of elements movable to operative or non-operative positions, the said elements being arranged in circumferential columns which represent stations and transverse rows which represent times, means for each circumferential column 40 adapted to be actuated by elements in the columns at the times represented by the transverse rows, an equal number of detaining means mechanically operated by said last mentioned means, an equal number of detainable discs fixed to a 45 shaft rotatable at the times represented by the transverse rows whereby an element in operative position in a transverse row detains a corresponding disc and the shaft against further rotation at the time represented by the element's transverse row, and means associated with the shaft 50 for setting the tuning means of the radio receiver to the stations represented by the columns of elements and corresponding discs.

27. In combination with a radio receiver, a 55 rotatable drum provided with a plurality of holes through its cylindrical wall the holes being arranged in circumferential columns which represent stations and in transverse rows which represent times, a plurality of pins positioned in 60 the holes and adapted for movement through the said wall to either operative or non-operative positions, resilient means associated with the said holes and pins whereby each pin is detained in its operative or non-operative positions, an 65 arm rotatable about its axis and movable along its axis, selecting means carried by said arm whereby after suitable movement of the arm one of the said pins may be moved to its operative position, manually operable means for moving 70 said arm along its axis whereby the said selecting means may be positioned over a desired circumferential column of pins, a second manually operable means for rotating said arm whereby 75 said selecting means may be positioned over a

- desired transverse row of pins, a time-scale means operated in a predetermined relation to said drum and associated with said second manually operable means, whereby the said second manually operable means may be adjusted with reference to said time-scale means when it is desired to move a pin in a particular transverse row to operative position, means associated with each column of pins operable by pins in operative position at the times represented by the transverse rows, a rotatable shaft, means for rotating the shaft at the times represented by the pins, means operated by the shaft for setting the tuning means of the radio receiver, and detaining means actuated by the means associated with each column of pins whereby the shaft rotation is stopped at a position corresponding to that required to tune in the station represented by the pin effecting the stopping.
- 20 28. In a device of the character described, a rotatable drum provided with a plurality of holes through its cylindrical wall, grooves extending circumferentially on the outer side of said wall, wires in the said grooves, and pins having axially spaced notches defining operative and non-operative positions positioned in the holes and engaged by the wires whereby the pins may be moved through the said wall and detained by the wires in operative or non-operative positions.
- 30 29. In a device of the character described, a drum rotatable in a timed manner, a plurality of actuating elements movable into operative or non-operative positions, the said actuating elements being arranged at the periphery of said drum in circumferential columns which represent conditions and in transverse rows which represent times, an arm rotatable about, and adapted to be moved along, its axis, selecting means carried by said arm whereby, after suitable movement of the arm, one of the said actuating elements may be moved to its operative position, manually operable means for moving said select-
- ing means over a desired circumferential column of actuating elements, a second manually operable means for moving said selecting means over a desired transverse row of actuating elements, and indicating means associated with said second manually operable means which move in timed relation to said drum so that the said selecting means may be set over a desired transverse row of actuating elements by referring the said second manually operable means to the said indicating means.
- 35 30. In a device of the character described, a rotatable drum, a plurality of actuating elements carried by said drum movable into operative or non-operative positions, manually operable means for moving a selected element into operative position, automatic means for moving said elements to inoperative position, and manually operable means for preventing, if desired, the action of said last mentioned means.
- 40 31. In a device of the character described, a rotatable drum provided with elements for effecting predetermined conditions at predetermined intervals of time, a pawl operated at regular intervals for rotating said drum, and cam means for preventing the action of the pawl for predetermined periods of time.
32. In combination with a radio receiver, movable means provided with actuating elements movable to operative or non-operative positions, manually operable means for moving a desired element to operative position, manually operable means for moving said elements to non-operative positions, means actuated by said elements for tuning the radio receiver to a desired station at a predetermined time, automatic means for moving an element to non-operative position after it has functioned to tune the receiver, and manually operable means for preventing, if desired, the action of said automatic means.

ROBERT H. VERKINS.
